UNITED STATES PATENT OFFICE.

MARY SPRATLEN, OF CONCORDIA, KANSAS.

COAL-CAR COVER.

1,210,556.

Specification of Letters Patent.

Patented Jan. 2, 1917.

Application filed September 11, 1916. Serial No. 119,562.

To all whom it may concern:

Be it known that I, MARY SPRATLEN, a citizen of the United States, residing at Concordia, in the county of Cloud and State of 5 Kansas, have invented certain new and useful Improvements in Coal-Car Covers, of which the following is a specification.

This invention relates to coal car covers.

One of the main objects of the invention is 10 to provide a cover for a coal car of simple construction and operation which can be easily moved into operative or inoperative position.

A further object is to provide a cover 15 which, when not in closed position, will not interfere with the loading or unloading of the car.

A still further object is to provide a cover which can be produced at a relatively low 20 cost.

Further objects will appear from the detail description.

In the drawings: Figure 1 is a fragmentary side view of a coal car with the cover 25 applied, Fig. 2 is a top plan view of the same, Fig. 3 is an end view of the cover as applied in closed position, and Fig. 4 is a modified form of the same.

Broadly stated my cover is composed of 30 two hingedly mounted rectangular sections adapted, when in operative position, to extend entirely over the top of a coal car. Each section of the cover is composed of a 35 rectangular frame 1 formed from a bar of steel bent into proper shape, the outer ends of the end arms 2 of which are bent to form eyes 3. A plurality of equally spaced longitudinally extending rods 4 have their ends secured to the end bars 2, and these bars are 40 interlaced with a plurality of equally spaced transversely extending bars 5. The bars 4 and 5 coöperate to form a strong and rigid grille which is firmly secured in the frame 1. The outer ends of the transverse bars 5 are 45 bent to form eyes similar to the eyes 3 of the end bars 2, and the eyes thus formed are all in alinement. A hinge rod 6 is mounted through U-straps 7 secured on the upper ends of the standards 8 mounted on the side 50 of the car 9. This hinge bar is inserted through the alined eyes of the transverse rods 5 and bars 2, and has its ends bent at right-angles to form arms 10. These arms are inserted into U-straps 11 secured to the 55 ends 9^a of the car. This prevents rotation

and longitudinal movement of the hinge rod. By this means each of the cover sections is hingedly mounted at its outer edge so as to swing freely about the rod 6.

The two sections of the cover are of such 60 length as to extend the full exterior length of the car and each of the sections is of a width somewhat greater than half the width of the car.

On the upper edge of each end 9^a of the 65 car is mounted an approximately V-shaped block 12, the apex of which is at the transverse center of the car. This block is detachably secured in position by means of hooks 13 pivoted on the end of the car which 70 engage with eyes 14 carried by the block. The block 12 provides means for supporting the ends of the cover sections which, when in operative position are slightly inclined 75 downwardly and outwardly, as shown in Figs. 3 and 4 of the drawings.

Each of the cover sections is provided at 80 each end, with a depending approximately triangular sheet metal guard plate 15. This plate is bent around the end bar 2 of the 85 cover section so as to be supported thereby and is adapted to extend downwardly in front of the block 12 with its lower edge in engagement with the upper edge of the end 90 of the car. Each of these plates is provided with an outwardly extending arm 16 95 provided at its outer end with an integral eye 17. The arms are so related that, when the cover sections are in closed position, the eyes 17 will be in superposed relation and will be 100 in alinement with a U-strap 18 secured to the block 12 and a U-strap 19 secured to the end of the car. A pin 20 is adapted to be inserted through the alined eyes and straps and is provided at its lower end with an 105 aperture to receive a sealing wire 21. This wire is intended to be passed through the lower end of the locking pin and through an eye or staple 22 secured to the end of the car, after which the ends of the wire are connected by a seal 23 in the usual manner. By this arrangement it is impossible to open 110 the car without breaking the seal 23. Even though the hooks 13 be moved out of engagement with the eyes 14, the block 12 would still be locked against movement by the pin 20 which would prevent outward movement of the block and the shields 15 which would prevent rotation of the block about the pin. In this manner the block 12, 110

the shields 15 and the pin 20, together with the U-straps and eyes, coöperate to prevent opening of the car or removal of the contents of the same.

5 Each of the sections of the cover is provided with a sheet metal strip or guard 24 securely clamped about the inner bar or side thereof. This guard acts as a protection for the inner side member of the cover section or 10 sections and also serves to secure the transverse rods 5 in spaced relation and to prevent these rods from becoming detached from the inner side bar of the cover section. These guard plates also render it possible to 15 effect a tight closure between the inner edges or sides of the two cover sections.

In Fig. 4 of the drawings, I have shown a modified securing means for the cover. In this figure, one of the guard plates is provided with a rectangular hook 25 pivotally secured thereto. This hook is adapted to be inserted through the eye 17 of the arm 16 carried by the other guard plate and through the U-strap 19 secured on the end of 25 the car. The lower end of the vertical arm of this hook is apertured to receive a sealing wire so as to secure the hook in operative position in the manner previously described for securing the end of the pin 20.

30 By removing the pin 20, the cover sections may be swung outwardly and downwardly about the hinge rods 6 so as to hang in an approximately vertical position in spaced relation to the side of the car. In this 35 position the cover sections will occupy very little space and will not interfere in any way with the loading or unloading of the car. Of course, when the cover sections have been moved into inoperative position in the manner described, the guard plates 15 will be 40 moved from in front of the blocks 12 so that these blocks may be quickly and easily detached from the ends of the car, if desired.

There may be slight changes made in the 45 construction and arrangement of the different parts of my invention without departing from the field and scope of the same, and I intend to include all such variations, as fall within the scope of the appended claims in 50 this application in which a preferred form only of my invention is disclosed.

What I claim is:

1. The combination of a car body, two cover sections extending half the width of the body and hingedly secured thereto at 55 their outer sides, said sections being adapted to entirely close the top of the car body when in operative position, a supporting block mounted on the end of the car and adapted to support the cover sections when in closed 60 position, guard plates extending in front of said block, and means for locking the block, the guard plates, and the cover sections against relative movement.

2. The combination of a car body, a cover 65 section hingedly secured to the side of the body at its outer side, said sections being adapted to entirely close the top of the car body when in operative position, a supporting block detachably secured on the upper 70 edge of the end of the car body adapted to support the cover sections when in closed position, guard plates carried by the cover sections and extending in front of the block when the cover is closed, and means for securing the block, the guard plates, and the 75 cover sections in operative position.

3. The combination of a car body, a cover section hingedly secured to each side of the body at the upper edge thereof, at its outer 80 side, said cover sections being adapted to entirely close the top of the car body when in operative position, a supporting block detachably secured on the upper edge of each end of the car body, guard plates carried by 85 the cover sections and extending, when in operative position, in front of said block, eyes carried by the plates and adapted to be in superposed relation when the plates are in operative position, a U-strap carried by the 90 block and in vertical alinement with said eyes, a U-strap secured to the end of the car in vertical alinement with the U-strap carried by the block, and a securing member 95 adapted to be secured to the alined eyes and straps.

In testimony whereof I affix my signature in presence of two witnesses.

MARY SPRATLEN.
